UNITED STATES PATENT OFFICE

116,434

DESIGN FOR A TRACTIVE VEHICLE

Rachel D. Raseman, Bloomfield Hills, Mich., as-
signor to Evans Products Company, Detroit,
Mich., a corporation of Delaware

Application November 7, 1938, Serial No. 80,922

Term of patent 14 years

To all whom it may concern:

Be it known that I, Rachel D. Raseman, a citizen of the United States, residing at Bloomfield Hills, in the county of Oakland and State of Michigan, have invented a new, original, and ornamental Design for a Tractive Vehicle, of which the following is a specification, reference being had to the accompanying drawing, forming a part thereof.

Fig. 1 is a perspective view of the cab end and one side of the vehicle showing my new design.

Fig. 2 is another perspective view showing a side and the other end of the same.

Fig. 3 is a reduced scale elevation of the side of the vehicle.

The other side of the vehicle is substantially like the side shown.

I claim:

The ornamental design for a tractive vehicle, substantially as shown and described.

RACHEL D. RASEMAN.
